UNITED STATES PATENT OFFICE.

HAMMOND CHARLES HASTINGS, OF RUGBY, ENGLAND, ASSIGNOR TO GENERAL ELECTRIC COMPANY, A CORPORATION OF NEW YORK.

ELECTROMAGNETIC SWITCH.

1,331,064.

Specification of Letters Patent.

Patented Feb. 17, 1920.

Application filed July 8, 1919. Serial No. 309,301.

To all whom it may concern:

Be it known that I, HAMMOND CHARLES HASTINGS, a subject of Great Britain, residing at Rugby, in the county of Warwickshire, England, have invented certain new and useful Improvements in Electromagnetic Switches, of which the following is a specification.

My invention relates to electromagnetic switches for controlling electric circuits and more particularly to switches of the lock-out type, which hold open when the current in a circuit is relatively high and close when the current drops to a predetermined value.

In the starting of electric motors, it has been the practice to employ a plurality of electromagnetic switches which close successively to cut out sections of resistance from the motor circuit and bring the motor up to speed. Various means have been devised for controlling the operation of the switches so that they will only close when the current is at a proper value, that is, after a switch has operated to cut out a section of resistance the next switch will not operate until the current has dropped to a safe value due to the speeding up of the motor.

A form of switch which has frequently been proposed for this purpose is one in which a shunt coil closes the switch and a series coil, instead of controlling the circuit of the shunt coil, positively prevents the switch from closing by actually holding it open, that is, the shunt coil pulls against the series or "holding-out" coil. The difficulty with this type of switch is that the value of current in the holding-out winding at which the switch will close depends upon the pull of the shunt coil, which, of course, will vary with the voltage and also with the temperature of the coil. In other words the "setting" of the switch, *i. e.*, the motor current value at which it closes, changes with the change of voltage. It also closes at one value of current in the series coil when the shunt coil is cold and another when it is at its operating temperature which is ordinarily about 60 degrees C.

The object of the present invention is to obtain a lock-out switch, which has a shunt closing and series lock-out coil, and is such that the balance between the closing and holding open forces will not be affected by

the variation in line volts and resistance of the shunt coil referred to above.

Referring to the drawings, Figures 1, 2 and 3 are curves showing various relations of the pull due to the closing and lock-out fluxes for various values of current in the shunt coil of the switch; Fig. 4 is a side elevation of a lock-out switch embodying my invention; Fig. 5 is an end view of the switch showing the series lock-out coil and its magnetic circuit; Fig. 6 is a part of a top view of the same; and Fig. 7 is a motor control system embodying my invention.

In carrying my invention into effect I utilize an operating magnet of the type described in the British Patent No. 11349 of 1911 and the British Patent No. 20534 of 1911 where a single magnetizing coil is used to produce two magnetic fluxes, which produce opposing forces on a single pivoted lever, which forms part of the path for each flux.

As described in the British Patent No. 11349 of 1911 the magnetic circuits are so proportioned that as the current changes in the magnetizing coil the percentage change in pull due to one of the fluxes is different from the corresponding percentage change in pull produced by the other flux. By changing the air gap in one or both of the flux paths it is possible to vary the strength of one of the forces compared with the other. This is explained in the British patents referred to above, and is illustrated by Fig. 1 of this specification.

Referring to the figure it is assumed, for purposes of illustration, that the two forces act at equal radii, and that the rocking lever which carries the moving contact is in the position corresponding to "contactor open." When the current in the magnetizing coil has the value O—D the forces due to the two fluxes are balanced, as is indicated by the intersection of the two curves at C. At values of current less than this the force due to the flux tending to close is always greater than the force due to the other flux, and at a particular value of current such as O—B, where the difference A—F in the closing and locking-out forces is just equal to the out of balance weight of the moving lever, the contactor will close. It would also close at any value of current lower than

this, where the difference between the closing and lock-out forces is not less than A—F, but for currents above O—B it will lock open. By increasing the air gap of the 5 lock-out flux path, so that the force produced by it for the same value of current is reduced, the point C where the two curves intersect may be moved along the curve, as shown in Fig. 2, where the point of intersection 10 has been moved to the point C—1 corresponding to an increased value of current O—D—1. It is obvious that the lock-out pull may be decreased in relation to the closing pull so that the two curves never 15 intersect. If a shunt coil is used for producing the two fluxes, and the maximum current in the coil is never as great as the value of O—D the magnetic force tending to close is always greater than that tending to lock 20 open, assuming that the magnetic circuits correspond to Fig. 2.

In carrying my invention into effect I utilize a shunt magnetizing coil in this way, and so proportion the two magnetic forces 25 that for the working range of the contactor the closing force produced by the shunt coil is always greater than the lock-out force produced by it. The magnetic paths of the two fluxes are also so proportioned that the 30 two curves are at the same distance apart (see Fig. 3) while the current in the shunt coil has any value between O—G and O—J. The change in the force produced by the lock-out part of the flux then exactly balances the change in the closing force due to 35 variation in the line volts and temperature of the coil. Thus the difference between the closing and lock-out forces produced by the shunt coil will be constant for the working 40 range of the coil corresponding to currents O—J and O—G, where O—G is the maximum current in the coil when maximum line volts are applied to the coil and the coil is cold, and O—J the current in the coil when 45 minimum line volts are applied and the coil is at maximum temperature.

In addition to this magnet producing two opposing forces I use a magnet energized by a series coil, the flux path of which is 50 independent of either of the paths of the flux produced by the shunt coil. The armature for this magnet is mounted on the lever which forms part of the shunt wound magnet, or may be an extension of this lever. 55 The arrangement is such that the force due to the series magnet tends to hold the contactor in the open position and the contactor will close when the closing force of the shunt coil is just greater than the sum of the 60 forces due to the out of balance weight of the moving lever, the lock-out force of the series coil, and the lock-out part of the shunt coil flux. As the closing force is made practically constant for the working range of 65 the contactor by the method described above,

the contactor can be set to close at various values of current in the series lock-out coil by altering the air gap in the circuit of the series lock-out coil flux, this circuit being independent of any of the other flux circuits. 70

One form of the contactor is as shown on Fig. 4. Figs. 5 and 6 are other views of the series lock-out magnet. 10 represents the shunt coil; 11 represents the core of this; 12 represents the armature for the closing flux; 14 the armature for the lock-out part of the flux of this coil; 17 represents the series lock-out coil; 18 the core of this; 19 represents a cap of magnetic material 80 used for altering the length of air gap in the magnetic circuit of the series magnet. The contactor is shown in the open position, in which case the lever 14 rests against the non-magnetic stop 20. The path of that part of the flux produced by 10 which tends to close 85 the contactor, is shown in full line arrow. The part of the flux produced by 10 which tends to lock out the contactor, passes through 16 and is shown by the dotted arrow. The double headed full line arrow indicates the magnetic path of the series lock-out magnet. A short circuiting copper band may be used around the limb 13 of the magnet to delay the growth of the closing 95 flux, as shown around the corresponding part of Fig. 1, British Patent No. 11,349 of 1911; this, however, is not essential to the scheme forming the subject of this specification. 90

Fig. 7 shows the diagram of the control 100 connections of a non-reversing series motor, in which the three contactors marked 2, 3 and 4 respectively are of the type forming the subject of this invention; the contactors close in the order 1, 2, 3, 4. The switches 105 marked S¹, S², S³ are auxiliary switches operated by the contactors; each auxiliary switch is opened when its corresponding contactor is opened, and is closed by the closing of its contactor. These auxiliary 110 switches are used to insure the correct sequence of closing of the contactors, if the controller is thrown quickly from the off to the fourth control position, in which case, if these switches were not used all the shunt 115 coils would be energized at the same time. The coils of the contactor are marked to correspond with Fig. 4, 10 being the shunt operating coils, 17 the series lock-out coils. 120

The operation of the scheme is as follows:—Contactor 1 will close if the controller is thrown to the first position; contactor 2 would follow if the controller were thrown to the second position, and the current in its lock-out coil had decreased to the 125 value at which it is set to close. Similarly, when the controller is thrown to the third position, the shunt coil of 3 is energized, but the contactor cannot close until the current in the series lock-out coil of this has de- 130

creased to the predetermined value. In the same manner contactor 4 will close when the controller is on the fourth point, if the current in its lock-out coil has decreased to the desired value.

5 In accordance with the provisions of the patent statutes, I have described the principle of operation of my invention, together with the apparatus which I now consider to 10 represent the best embodiment thereof, but I desire to have it understood that the apparatus shown is only illustrative and that the invention can be carried out by other means.

15 What I claim as new and desire to secure by Letters Patent of the United States, is:—

1. An electromagnetic switch of the lock-out type comprising a movable switch contact operating member and a shunt coil adapted to produce magnetic fluxes through 20 two parallel paths of both of which the movable member forms a part, one of said fluxes tending to close the switch while the other tends to hold it open, the path of the holding open flux having a reluctance of 25 such value that the force tending to close the switch is substantially constant despite variations in the current in the shunt coil due to variations in the impressed voltage and the temperature of the coil, and a series

coil having a flux path independent of the 30 flux paths of the said shunt coil for holding the switch open until the current in said series coil drops to a predetermined value.

2. An electromagnetic switch of the lock-out type comprising a movable switch contact operating member and a shunt coil adapted to produce magnetic fluxes through 35 two parallel paths of both of which the movable member forms a part, one of said fluxes tending to close the switch while the other tends to hold it open, the path of the holding open flux having an air gap of such length that the force tending to close the switch is substantially constant despite variations in the current in the shunt coil due to 40 variations in the impressed voltage and the temperature of the coil, and a series coil having a flux path independent of the flux paths of the said shunt coil for holding the switch open until the current in said series 45 coil drops to a predetermined value.

In witness whereof I have hereunto set my hand this 13th day of June, 1919.

HAMMOND CHARLES HASTINGS.
